ABSTRACT

A scaffold which is positionable in a window opening to extend outward therefrom for supporting a workman and equipment exteriorly of a window mounted in the opening. The scaffold includes a platform having a flat surface, with a hook portion on one end of the platform and a pair of cross-bar holding ears adjacent to the hook. A cross-bar is removably mounted in the ears for engagement with the interior of a building wall. A safety rail is mounted on the platform adjacent to the end, extendable exteriorly of the window. A support brace is hingedly connected to the bottom of the platform and is engageable with the exterior of a building wall to support the platform. The support brace and the safety rail are interlocked when in an extended attitude, and both may be folded against the platform.

COLLAPSIBLE WINDOW SCAFFOLD

BACKGROUND OF THE INVENTION

This invention relates to a particular form of scaffold, that is, one which is mountable in a window opening so that a platform extends outwardly from a window opening while a portion of the platform is secured inside the window opening. The scaffold construction is such that a workman may step out onto the scaffold to work on or about the window. Scaffolds of this general type are well-known. Individuals using a scaffold of this type are generally in a hurry to accomplish their job. Many scaffolds have provisions for safety devices, but a workman often fails to use a safety device for the sake of expediency. The result is that a workman may be seriously injured for failure to utilize a protective device.

SUMMARY OF THE INVENTION

The scaffold which is the subject of the present invention is one which is adapted for mounting in a window opening. The present scaffold is collapsible in that it may be folded up into a compact unit to facilitate handling and for installation in a window opening. The scaffold construction is such that when the scaffold is installed in a window opening, the scaffold includes a guard rail which protects a workman who stands on the scaffold. The construction is such that in order to mount the scaffold in a window, the guard rail must also be erected, thereby requiring a workman to utilize a guard rail.

The scaffold includes a substantially flat platform which has a hook portion at one end. A pair of ears is mounted adjacent to the hook portion, which ears removably receive a cross-bar, which cross-bar is engageable with the interior of a building wall. A safety rail is hingedly mounted on the platform adjacent to the other end of the platform. A support brace is hingedly connected to the platform adjacent to the same exterior end of the platform. The support brace and the safety rail are interlocked when the support brace is placed into an attitude for supporting the platform and the guard rail is in a raised position.

It is therefore one of the principal objects of the present invention to provide an improved construction for a collapsible window scaffold which includes a safety rail.

It is another object of the herein-disclosed invention to provide a collapsible window scaffold having a platform with vertical supports adjacent to the opposite ends of the platform.

It is still another object of the instant invention to provide a collapsible window scaffold which may be mounted on buildings having walls of various thicknesses.

Other objects and uses of this invention will become apparent to those skilled in the art upon a perusal of the following specification in light of the accompanying drawings.

BRIEF DESCRIPTION OF THE DRAWINGS

FIG. 1 is a perspective view of a scaffold embodying the herein-disclosed invention, shown in an extended attitude;

FIG. 2 is a cross-sectional elevational view, showing the scaffold of FIG. 1 mounted in a window opening;

FIG. 3 is a partial end elevational view of a portion of the scaffold of FIG. 1, with a portion of a platform broken away in order to show better the construction of the scaffold;

FIG. 4 is a cross-sectional view taken on line 4-4 of FIG. 2;

FIG. 5 is a side elevational view, with a portion of the platform broken away in order to show better the construction of the instant scaffold, but showing the scaffold in a partially collapsed attitude; and

FIG. 6 is a side elevational view of the scaffold of FIG. 1, shown in a collapsed attitude.

DESCRIPTION OF THE PREFERRED EMBODIMENT

Referring now to the drawings, and especially to FIGS. 1 and 2, a scaffold embodying the present invention and generally indicated by numeral 10 is shown therein. The scaffold 10 generally includes a continuous sheet platform 12, with a frame 14 mounted on the upper surface of the platform adjacent to one end thereof. A safety rail 16 is hingedly connected to the frame 14. A support brace generally indicated by numeral 18 is hingedly connected to the underside of the platform 10 adjacent to said one end and is releasably engageable with a portion of the safety rail 16. A lock bar 20 is removably connected to the platform 12 adjacent to the other end thereof for holding the scaffold in a window opening, as will be described in detail hereinafter.

The platform 12 has a continuous aluminum sheet support surface 22 substantially uniform in width, with a hook portion 24 formed integral with the end adjacent to the lock bar. A rubber cover 26 is secured to the hook portion. The platform 12 has a pair of apertured bar ears 28 formed integral with the sheet support surface 22. The ears 28 are perpendicular to that surface and are adapted to receive slideably the lock bar 20. A hand aperture 30 is formed in the sheet support surface 22 to provide a convenient means for grasping the platform while handling the scaffold 10. A door track 32 is fixed to the underside of the support surface 22 and slideably receives an aperture door 34, which slides along the door track 32 to provide a closure for the aperture 30. The door 34 includes a tab 36 to provide a convenient means for grasping the door 34 while sliding it along the track 32. The platform has a pair of reinforcement channels 38 fixed to the underside thereof along the lateral edges of the platform. The reinforcement channels 38 do not extend the length of the sheet support surface, but rather terminate short of the hook portion. The support surface 32 includes a lock aperture 40 at the end opposite the hook portion 24 to receive a part of the support brace, as will be described below.

As may be best seen in FIG. 1, the frame 14 includes a pair of outer uprights 42, which are formed integral with the support surface 22. A pair of inner uprights 44 is also formed integral with the support surface. The outer and inner uprights 42 and 44 are perpendicular to the support surface. A pair of side bars 46 is fixed to the upper ends of each of a pair of the outer and inner uprights 42 and 44 and extend therebetween parallel to the reinforcement channels 38. An outer bar 48 is fixed to the upper ends of the outer uprights 42. The frame 14 includes a pair of sockets 50, which sockets are fixed to respective inner uprights 44.

As was mentioned above, the safety rail 16 is pivotally connected to the frame 14. The safety rail includes a pair of pivot posts 52, each of which is pivotally connected to a respective outer upright 42 by means of a respective bolt 54. A rail lock bar 56 extends between the lower ends of the pivot posts 52. A reinforcement gusset 58 is fixed to each of the pivot posts and the rail lock bar 56 at the intersection of each pivot post with the rail lock bar. At the top of each of the pivot posts, there is a pair of outer hinge plates 60. Each of the pairs of hinge plates is fixed to its pivot post and pivotally receives a hand rail 62 between each pair of outer hinge plates. The hand rail includes a pair of hand rail arms 64, which hand rail arms are pivotally connected to respective pairs of outer hinge plates, as may be seen in FIG. 1. A back or cross-member 66 is formed integral with the arms 62. A pair of inner hinge plates 68 is pivotally connected to each of the free ends of the hand rail arms 64. An inner post 70 is fixed to each pair of inner hinge plates 68. Each inner post 70 has a post offset 72 which slideably fits into its respective socket 50. A pair of rail clips 74 is fixed to the support surface 22 adjacent to inner upright 44 for releasable engagement with its respective inner post 70, as will be described hereinafter.

The construction of the support brace may be best seen in FIGS. 2 and 3. The support brace includes two pairs of brace plates 76 mounted on the underside of the support surface 22 and being spaced away from the hook portion 24. A U-shaped lock bracket 78 is pivotally connected to the pairs of brace plates 76. The U-shaped lock bracket includes a pair of arms 80, with a collar 82 mounted on each of the arms. A bolt 84 extends through each pair of brace plates 76 through the respective collars 82 and the respective arms 80. The bolts 84 act as pivot pins for the lock bracket 78. The lock bracket also includes a head 86 formed integral with the arms 80. A latch 88 is fixed to the head 86 and is positionable in the lock aperture 40. The latch has a notch 90, which receives the rail lock bar 56 of the hand rail to lock releasably the support brace to the safety rail.

The support brace 18 also includes an abutment bracket 92. Bracket 92 has a pair of hollow arms 94 which slideably receive the respective arms 80 of the U-shaped lock bracket. The arms 94 have an abutment head 96 formed integral therewith for engagement with an exterior wall of a building. A tabular spacer 98 is positioned between the end of each of the hollow arms 94 and the respective collars 82 so as to adjust the overall length of the support brace, thereby accommodating the length of the brace to a building wall thickness. A pair of brace clips 100 is fixed to the underside of the support surface 22 for releasable engagement with the arms 94 of the abutment bracket 92.

As may be seen in FIG. 6, the instant scaffold may be folded to a compact unit for ease in handling. Once it is determined that the scaffold is to be erected, the thickness of a building wall is determined and appropriate sized spacers 98 are positioned between the ends of the hollow arms 94 and the respective collars 82. The operator of the scaffold then raises a window 102 and positions a portion of the scaffold in a window aperture 104. He opens the door 34, which allows him to place his hand in an aperture for manipulating the overall scaffold. With a portion of the scaffold resting

in the window aperture, he inserts the lock bar 20 in through the bar ears 28 and then pushes the scaffold forward. The support brace 18, which had been released from the brace clips 100, drops down. By pulling upward on the support surface 22, the support brace 18 drops down and engages the outer surface of a building wall 106. Since the length of the support bracket had been adjusted to a proper length for the building wall thickness, the lock bar 20 engages the inner surface of the building wall when the platform is substantially horizontal. The support bracket provides vertical support at the furthermost or outer end of the platform 12; and the inner end adjacent to the hook portion is supported vertically by the building wall. The hand rail 16 is raised, and the inner post offsets 72 are positioned in the sockets 50 to hold the safety rail in an upright position; and the rail lock bar 56 is positioned in the notch 90 of latch 88 to interlock the safety rail and the support bracket. With the safety rail in the upright position and interlocked with the support bracket, a workman then may proceed to step onto the platform 12 and be supported thereby.

As may be seen in FIG. 2, the support surface 22 is very thin at the point that the support surface 22 engages the building wall. Window 102 may be closed substantially all the way. Thus, a workman may either wash a window or repair a window entirely from the outside. The instant scaffold provides a continuous surface for standing and working, with no obstructions in the surface, and has a substantially uniform width. The frame 14 provides a safety railing for equipment such as buckets or other tools so that there is less likelihood of anything dropping from the platform and providing a hazard to workmen or unsuspecting third persons walking below the platform. Furthermore, the frame also provides a lower retaining rail, which further prevents a workman from easily slipping off the platform. There are no obstructions in the work surface between the locking bar 20 and the rail lock bar 56 of the safety rail. The safety rail 16 provides a greater degree of stability for a workman standing on the platform when there is wind, and also provides a psychological support for the workman.

The arrangement of the support of the platform provides a platform which has a good balance. The end of the platform adjacent to the hook portion is supported by a window frame; and the outer end of the platform is supported by the support brace. The weight of the workman is between the two ends of the support so that there is no likelihood of the platform tipping during normal working.

In order to remove the platform, the workman need only leave the platform and then the scaffold may be removed from the window. The removal of the scaffold may be accomplished in either of two methods. Should the window opening be high enough, it is possible for the scaffold to be removed in an erected attitude simply by raising the window, grasping the support surface through the aperture and raising the platform so that the head 96 of the abutment bracket is raised to a position to be moved into the window aperture. If the window opening is too small to accept the erected scaffold, then the scaffold may be partially folded while in the mounted position. The platform is tilted slightly to release the support brace from engagement with the

building wall, thereby allowing the interconnection between the safety rail and the support brace to be disengaged, thereby allowing the safety rail to be lowered and thus pull the scaffold in through the window aperture. Once the scaffold is brought in through the window aperture, the inner posts 70 are positioned in the rail clips 74 to hold the hand rail against the platform; and the hollow arms 94 are placed into engagement with the brace clips 100 to keep the support brace up against the platform. This allows the scaffold to be folded easily and to be handled easily once it is folded. The construction of most of the parts of the scaffold is aluminum, which renders the scaffold to be of light weight and economical to manufacture.

Although a specific embodiment of the present invention has been shown and described in detail above, it is readily apparent that those skilled in the art may make various modifications and changes in the present invention without departing from the spirit and scope of the present invention. It is to be expressly understood that the present invention is limited only by the appended claims.

What is claimed is:

1. A scaffold adapted for mounting in a window opening and extending outward therefrom for supporting a workman exteriorally of the window, comprising, a continuous platform, a pair of bar ears connected to the platform adjacent to one end thereof, a cross-bar removably mounted in the bar ears, a safety rail hingedly connected to the platform adjacent to the other end thereof, said safety rail being foldable to an attitude substantially parallel to the upper side of the platform, a support brace hingedly connected to the platform and being positioned adjacent to the underside of the platform, said support brace having a pair of arms and an abutting bracket being positionable substantially parallel to the underside of the platform, said support brace including a latch extendible through the platform, said safety rail includes a first pair of uprights hingedly connected to the platform, a lock bar connecting the first pair of uprights and releasably engageable with the latch, a U-shaped hand rail hingedly connected to the first pair of uprights, a second pair of uprights, each of said uprights of the second pair having one end hingedly connected to the hand rail and the other end releasably locked to the platform, and means interconnecting the support brace and the safety rail, whereby pivoting of the safety rail releases the support brace from an attitude for supporting the platform for pivoting to an attitude adjacent to the platform.

2. A scaffold adapted for mounting in a window opening and extending outward therefrom for supporting a workman exteriorally of the window, comprising, a continuous platform, a pair of bar ears connected to the platform adjacent to one end thereof, a cross-bar removably mounted in the bar ears, a safety rail hingedly connected to the platform adjacent to the other end thereof, said safety rail being foldable to an attitude substantially parallel to the upper side of the platform, said safety rail including a pair of pivot posts hingedly connected to the platform, a U-shaped hand rail hingedly connected to the pivot posts, a pair of

inner posts having one end hingedly connected to the hand rail and the other end being releasably locked to the platform in an upright attitude, a support brace hingedly connected to the platform and being positioned adjacent to the underside of the platform, said support brace having a pair of arms and an abutting bracket being positionable substantially parallel to the underside of the platform, and means interconnecting the support brace and the safety rail, whereby pivoting of the safety rail releases the support brace from an attitude for supporting the platform for pivoting to an attitude adjacent to the platform.

3. A scaffold adapted for mounting in a window opening and extending outward therefrom for supporting a workman exteriorally of the window, comprising, a continuous platform; a pair of bar ears connected to the platform adjacent to one end thereof; a cross-bar removably mounted in the bar ears; said continuous platform including a thin sheet support surface having a substantially uniform width for the length of the platform, and a pair of reinforcement members mounted on the underside of the support sheet extending from the end opposite the end adjacent to the bar ears and terminating a distance between the reinforcement members and the bar ears great enough to accommodate a building wall between the ends of the reinforcement members and the lock bar; a safety rail hingedly connected to the platform adjacent to the other end thereof; said safety rail being foldable to an attitude substantially parallel to the upper side of the platform; a support brace hingedly connected to the platform and being positioned adjacent to the underside of the platform; said support brace having a pair of arms and an abutting bracket being positionable substantially parallel to the underside of the platform; a frame mounted on the upper side of the platform and extending from the end opposite the end adjacent to the pair of bar ears toward the bar ears, said frame having a pair of inner uprights formed integral with the supporting surface and a pair of outer uprights formed integral with the supporting surface; said safety rail being hingedly mounted on the frame and including a pair of pivot posts pivotedly connected to the outer uprights of the frame, a hand rail pivotedly connected to the pair of pivot posts, and a pair of inner posts pivotedly connected to the hand rail and being releasably engageable with the frame to allow the safety rail to be folded against the upper surface of the platform; said support brace having a U-shaped lock bracket pivotedly connected to the underside of the platform, said abutment bracket being slideably engageable with the arms of the support brace, and spacers removably positionable in engagement with the ends of the abutment bracket for determining the length of the support brace; a rail lock bar fixed to the pivot posts of the safety rail and a latch releasably engageable with the rail lock bar and being fixed to the U-shaped lock bracket for interconnecting the support brace and the safety rail; whereby pivoting of the safety rail releases the support brace from an attitude for supporting the platform for pivoting to an attitude adjacent to the platform.
